2,136,482

ART OF SHOEMAKING

Oscar C. Adams, Lynn, Mass., assignor to United Shoe Machinery Corporation, Paterson, N. J., a corporation of New Jersey

Application January 31, 1936, Serial No. 61,784

5 Claims. (Cl. 12—142)

This invention relates to methods of making welting, and to methods of making shoes in which the welting is employed.

Objects of the invention are to facilitate the production of welt shoes and to reduce their cost.

In one aspect the invention relates to a method of making welting comprising forming a flap by channeling a piece of welting, substantially rectangular in cross-section, by a cut entering the grain face of the welting and extending toward the inner edge of the welting in a plane substantially parallel to its upper and lower faces, the cut stopping short of the inner edge of the welt, and then bending or turning the flap about the edge of the welt through 180 degrees.

In another aspect the invention comprises a method of making shoes which consists in attaching a welt channelled as above explained to an outsole with its outer edge substantially flush with the edge of the outsole, flattening down the flap formed by the channeling operation, then applying cement to the thus-exposed split surfaces of the welting, working an upper over an insole and securing it in lasted position, roughening the upper, applying cement thereto, and finally cement-attaching the welt to the upper.

These and other aspects of the invention will appear more fully from the following description when read in connection with the accompanying drawing and will be pointed out in the appended claims.

35 In the drawing,

Fig. 1 is an enlarged perspective view of a piece of welting channelled in accordance with the present invention;

Fig. 2 is a perspective view showing an outsole having welting channelled as shown in Fig. 1 attached to its periphery with the channel flap in process of being laid inwardly to provide a welt having an inner split surface of wide extent;

Fig. 3 is an enlarged perspective view of the welting showing more in detail how the channel flap is spread out and flattened;

Figs. 4, 5 and 6 are fragmentary sectional views showing different ways of attaching the welt to the outsole and different forms of filling material;

Fig. 7 is a detail view in perspective and section of the sole and filler showing reduction of the margin of the filler;

Fig. 8 is a detail view in perspective and section showing rounding of the filler and reduction of the sole; and

Fig. 9 is an enlarged fragmentary sectional view of a sole with the welt attached thereto by cement and a filler applied to the sole in the area defined by the inner edge of the welt, the

sole being trimmed, edge set, and edge finished before attachment to a shoe.

In practising the present invention in the manufacture of low-priced welt shoes, welting is first prepared as disclosed in Fig. 1. The welting 10, preferably substantially rectangular in cross-section, has a grain face 12 and a flesh face 14. The welting is channelled by a cut beginning at a line 16 which may be, for example, substantially one third of the width of the welting from its outer edge, the channeling cut extending into the welting and toward the inner edge of the welting along a plane substantially midway between the upper and lower surfaces of the welting, the cut stopping short of the inner edge 15 of the welting a distance substantially equal to one half the original thickness of the welting. The channel flap 18 thus formed may then be raised and turned back through 180 degrees, as shown in Fig. 3, thus producing welting of increased width having a thicker portion at its outer edge with a grain upper face and a wide extension of reduced thickness having a split upper face, the inner half of the portion of reduced thickness having a grain surface 20 on its lower side; or, if preferred, the raising of the channel flap may be postponed until after the welt has been attached to the outsole 22, as is hereinafter described.

If, for instance, welting $\frac{1}{8}$ of an inch wide and three irons in thickness is thus treated, welting having a total width of about $\frac{1}{4}$ of an inch and having a grain face about $\frac{1}{8}$ of an inch wide and an adjacent split face $\frac{1}{16}$ of an inch wide is produced. Welting thus prepared, and preferably before the flap 18 is turned over, since it is more convenient to handle in that condition, is attached to the periphery of the outsole 22, preferably with the outer edge of the welting flush with the edge of the sole. This attachment may be effected with cement temporarily or permanently, depending upon the kind of cement used. For temporary use rubber cement or latex may be employed and for permanent attachment pyroxylin cement or the polymerized chloroprene cement disclosed in an application for Letters Patent of the United States Serial No. 51,114, filed November 22, 1935, in the name of Alexander D. Macdonald, the latter being preferred because of its greater flexibility. If desired, the welt may be sewed to the outsole without the use of either temporary or permanent cement.

As shown in Fig. 6, the outsole stitches 24 extend through the portion of the grain surface 12 which remains upon the outer face of the welt and through the sole, the stitches 24 being hidden if desired in a channel 26, as shown in Fig. 5. After the welting is attached to the sole, the flap 18 may be bent inwardly and flat-

tened down against a filler 28 first located on the outsole inside the space defined by the inner edge of the welt. As shown in Fig. 5, a thinner marginal portion of the filler 28 extends under the flap 18 and serves as a cushion to support the inner portion of the welting. In other cases, that is, where the curvature of the last bottom is more pronounced, it may be desirable first to turn the flap 18 inwardly and then apply a filler 28' only in the space defined by the inner edge of the flap 18, as shown in Fig. 9.

If a solid filling material such as leather or a leather substitute is employed, it is preferable first to attach an over-size piece of filling material 28 to the outsole 10, as shown in dash-and-dot lines in Fig. 7, and then to reduce the inner margin of the filler 28 at a predetermined distance from the edge face of the sole. This may conveniently be done by employing a channelling machine such as that disclosed in Letters Patent of the United States No. 1,115,046, granted October 27, 1914, in the name of H. W. Winter, equipped with a knife suitable for the purpose. The excess material is thus removed from the filler 28 to give it the shape shown in full lines in Fig. 7, so that its reduced marginal portion will be disposed exactly under the flap 18 when the flap is laid down against it. Where the form of filler 28' is preferred, the marginal portion of the filler may be trimmed away at a predetermined distance from the edge of the sole 10, as indicated in Fig. 8, to form thereon a vertical edge face located just inside the inner edge of the flap 18. When either form of filler 28 is used, the marginal portion of the outsole 10 may be reduced in thickness at the same time that the filler is shaped. Such a reduction is indicated by dash-and-dot lines in Fig. 8.

After the welting is pre-attached to the sole, the sole may be completely edge and bottom finished (for example, its edge may be trimmed, stained and set) prior to its attachment to the shoe, such a pre-finished sole with a welt pre-attached thereto being indicated in Fig. 9.

In the operation of channelling the welting 10, perforations may be formed through the welting as shown at 17 in Fig. 1. These perforations may be made by providing suitable teeth on the feed wheel by which the welting is fed through the channelling machine. When the flap 18 is opened up as shown in Fig. 3, two lines of perforations 17 will appear upon the surface of the welting which is to be cement-attached to the upper. These perforations may be made as close together as is desired and, since they will become filled by the cement which is applied to the split surfaces of the welting, will tend to enhance the holding power of the cement.

The preparation of the shoe for the attachment of the outsole and welt as above described may be the same as the preparation of a shoe to receive the usual cement-attached sole; that is, an upper 30 and a lining 32 may be worked over a plain or unchanneled insole 34 in any usual manner and secured to the insole in lasted position. The overlasted portion of the upper may then be roughened and cemented and the cement allowed to dry. The split surfaces on the upper face of the welting will also be cemented and allowed to dry. The cement employed may be the usual pyroxylin cement used for cement-sole-attaching or it may be the polymerized chloroprene cement disclosed in the Macdonald application referred to above. Then, after activation of the cement in case pyroxylin

cement is used, the shoe and sole are brought together in the proper relation to each other and pressure is applied to produce a permanent bond between the overlasted upper and the thinner portion of the welt. When necessary or desirable, a felt or other filler 36 may be applied to the shoe bottom before the shoe and sole are brought together.

It is to be understood that, if desired, the welting may be first attached to the sole and then channeled, though I consider it preferable to channel the welting in long lengths before it is attached to the sole.

Having thus described my invention, what I claim as new and desire to secure by Letters Patent of the United States is:

1. That improvement in methods of making welting which consists in separating the inner portion of the welting into two layers of substantially equal thickness connected at their inner edges, and turning the grain layer upside down to increase the width of the welting and provide welting having a grain face along its outer edge and having a split face of wider extent along its other edge at the same side of the welting.

2. That improvement in methods of making welting which consists in separating one marginal portion of the welting into two layers of substantially equal thickness connected at one edge, simultaneously perforating the two layers, and turning one layer upside down to increase the width of the welting and to double the number of perforations therein.

3. That improvement in methods of making leather welting which consists in splitting approximately from half to two thirds of the width of the welting on its grain side into two layers of substantially equal thickness connected along one edge of the original strip of welting, and turning one layer away from the other through 180 degrees to increase the width of the welting thus providing welting having a wide split face and a narrow grain face.

4. That method of making shoes which consists in providing a piece of welting channeled to form a lip connected to the welting at one edge, turning the lip through 180 degrees to expose the split surfaces, attaching the non-split edge of the welt to the peripheral portion of an outsole, lasting an upper over an insole and securing it in lasted position, preparing the overlasted upper for cement-attachment, and cement-attaching the sole to the shoe, the cement bond being principally or wholly between the overlasted upper and the split surface of the inwardly extending reduced portion of the welting.

5. That improvement in methods of making shoes which consists in providing a piece of leather welting channeled at its inner portion to form a lip connected to the welting along its inner edge, attaching the outer edge of the welting to the peripheral portion of an outsole, turning the lip inwardly to expose the split surfaces, lasting an upper over an insole and securing it in lasted position, roughening the upper, cementing the split surfaces of the welting, and cement-attaching the sole to the shoe, the cement bond being principally or wholly between the overlasted upper and the inwardly extending reduced portion of the welting.
